INCINERATOR

Mark H. Allen, Greenville, S. C., assignor to The
Allen Company, Greenville, S. C., a corporation
of South Carolina

Application March 21, 1935, Serial No. 12,282

18 Claims. (Cl. 110—12)

My invention relates to improvements in incinerators.

An important object of the invention is to provide an incinerator for the odorless destruction of refuse, such as garbage, industrial waste, municipal waste, hospital waste, and high moisture content refuse such as sewer sludge and non-digestable sewer accumulations.

A further object of the invention is to provide an incinerator or furnace of the above mentioned character so constructed that the maximum heat reflection is obtained upon the burning and unburned refuse whereby a high efficiency in operation is obtainable.

A further object of the invention is to provide an incinerator of the above mentioned character having means to effect a turbulence of the gases for securing complete combustion and deodorization prior to being discharged to the atmosphere.

Other objects and advantages of the invention will be apparent during the course of the following description.

In the accompanying drawings forming a part of this application and in which like numerals are employed to designate like parts throughout the same,

Figure 1 is a perspective view of an incinerator or furnace embodying my invention,

Figure 2 is a central vertical longitudinal section through the same,

Figure 3 is a transverse section taken on line 3—3 of Figure 2,

Figure 4 is a similar view taken on line 4—4 of Figure 2,

Figure 5 is a horizontal cross-section taken on line 5—5 of Figure 2,

Figure 6 is a similar view taken on line 6—6 of Figure 2, and,

Figure 7 is a diagrammatic plan view, showing the dome construction.

In the drawings, wherein for the purpose of illustration is shown a preferred embodiment of my invention, the numeral 10 designates the main casing of the incinerator or furnace which may be formed of any suitable material, such as plastic refractory material which will harden upon being heated, or fire brick or blocks. This main casing is preferably enclosed within an outer casing 11, which may be formed of common brick, and which may be suitably stiffened and held in place by buck stays 12 or the like.

The casing or shell 10 embodies a main combustion chamber 13 which is preferably rectangular in horizontal section and somewhat elongated

and is provided at its rear end with a stoke passage 14, adapted to be closed by a door 15, and at its forward end with a stoke or clinker passage 16, adapted to be covered and uncovered by a vertically movable door 17, operating in guides 18. This door is raised by a cable 19, wound upon a spool 20, turned by a hand-wheel 21, and is returned to the closed position by gravity. At the bottom of the main combustion chamber 13 is a generally horizontal main drying deck 22, preferably inclined slightly toward the forward end of the chamber, and disposed forwardly of the drying deck 22 are horizontal burning decks 23, disposed in stepped relation. The burning decks 23 are supported by vertically arranged grates 24. The decks 22 and 23 and the vertically arranged grates 24 extend throughout the entire width of the main combustion chamber 13 and the vertical grates 24 are preferably anchored within the side walls of this combustion chamber. The vertical grates 24 have openings 25 for the passage of air. The burning decks 23 may be formed of blocks, if desired, while the vertical grates may be formed of metal or any other suitable material. The lowermost vertical grate 24 is arranged above and adjacent to a vertical bridge wall 26, and an ash pit 27 is disposed forwardly of the bridge wall and access is had to the ends of this ash pit through openings covered by doors 28 or the like. Arranged above this ash pit is a horizontal grate 29, which is stationary or movable, and this grate is disposed in stepped relation to the lowermost burning platform 23 and is disposed in advance of the same. The drying deck 22 is imperforate and extends to the end wall of the furnace in the direction of travel of the heated gases or products of combustion and is attached to such end wall and preferably formed integral therewith. The burning decks 23 are formed of blocks and are therefore imperforate or substantially so. The burning decks are arranged at different elevations and the grates 24 provide air passages between these decks. By having the drying deck extending to the end wall, the stoke passage 14 may be formed in such end wall and is therefore at the end of the drying deck remote from the burning decks.

The top 30' of the main combustion chamber includes a generally dome-shaped inner surface or wall 30, constituting a heat reflecting surface, disposed to reflect heat over the entire surfaces of the drying deck 22, the burning decks 23 and the grate 29. This inner reflecting surface 30 is preferably formed in segments 31, which are longitudinally curved, but transversely straight, but

the assembled segments produce a generally spherically curved or dome-shaped reflecting surface. At their bottoms, the segments 31 merge into surfaces 32 which are vertical with respect 5 to the platforms 22 and 23. The generally spherically curved surface 30 and wall 30' also serve to radiate heat over the drying deck 22, burning deck 23 and grate 29, as is obvious. The top 30' of the main combustion chamber is provided 10 with a charging opening 33, through which the refuse is introduced in such a manner as to prevent the escape of the gases from the combustion chamber, a slide door or the like (not shown) being employed to cover the opening. The 15 charging opening 33 is arranged directly over the drying deck 22 so that the refuse will initially pass thereon, such refuse being moved forwardly through the combustion chamber over the several burning decks until the remaining unburned portion passes to the grate 29, where combustion is completed, the ashes passing into the ash pit 27.

As shown in Figure 7, the surface or wall 30 is spherical or in the shape of a dome, and it 25 rises from the chamber 13, which is an elongated rectangular figure. The center of the surface 30 is in the central longitudinal axis of the chamber 13, but this center is never the rear end of the chamber 13. The center of the dome-shaped surface could also be equi-distantly spaced 30 from the ends of the chamber 13. The dome-shaped surface may rise from a chamber in the form of a square with its center coinciding with the center of the square.

35 Means are provided for preheating air and supplying air into the combustion chamber, and causing such preheated air to pass over and between the burning decks, and also through the horizontal grate 29, when desired. This means comprises 40 down draft air ducts 34, having draft controlling doors 35. These air ducts 34 extend across or in proximity to the main combustion chamber 13 and are heated by this chamber. These air ducts have their lower outlet ends 36 leading into 45 a chamber 37 at the ends thereof, and this chamber is disposed beneath the burning decks 23. The preheated air supplied to this chamber passes through the openings in the vertical grates 24 and therefore passes between the burning decks 50 23. Some of this air may also pass through a horizontal duct 38, formed in the vertical bridge wall 26, and there is a damper 39 in the passage 33, to regulate the travel of air therethrough. It is thus seen that preheated air passes in a 55 forwardly direction between the decks 23 and may also pass upwardly through the grate 29, and this air, with the products of combustion, then travel rearwardly and upwardly over the burning decks 23 and the drying deck 22.

60 Beneath the drying deck 22 is a gas combustion or deodorizing chamber 40, which has no communication with the main combustion chamber, except by down flues, to be described. The drying deck 22 constitutes the top of this gas 65 combustion chamber and continues downwardly in the form of a vertical bridge wall 41. The numeral 42 designates down flues, communicating at their upper end with the rear end of the combustion chamber 13, at points above the upper 70 surface of the drying deck 22, these flues 42 passing through the reflecting surface 30, as shown. The flues 42 lead downwardly, see more particularly Figure 4, and discharge into the gas combustion chamber 40 near the opposite ends thereof. 75 This gas combustion chamber is provided with

baffles 43, so that a turbulence of the gases is effected and complete combustion and deodorization occurs. The chamber 40 has communication at one end with a passage 44, which leads to the stack, and the passage 44 has a damper 44' as 5 shown. The chamber 40 may have communication at either end with the stack, or at both ends, if desired.

Chamber 13 is provided with observation ports 10 45, covered with glass or the like, and stoke doors 46, which, with stoke doors 45 and 47, afford access to all parts of the combustion chamber. Access is also had to the opposite ends of the chamber 37 through doors 47, and into the opposite ends of the chamber 40 through doors 48. 15 These doors 48 may be manipulated to supply additional air to the gas combustion chamber 40, if desired.

The numeral 49 designates burners, adapted to use as fuel, natural gas, artificial coal gas, sewer 20 gas, or oil. These burners serve to promote combustion and to raise the temperature of the main furnace sufficiently high to assure the complete burning of all combustibles. They also serve to supply secondary air into chamber 13, to effect 25 combustion.

The operation of the incinerator or furnace is as follows:

The burners 49 are set into operation which 30 supply flames for initially heating the furnace and promoting combustion, such burners being also employed to supply secondary air. High moisture content refuse is introduced into the combustion chamber 13, through the charging opening 33 without the escape of any considerable amount of heated gases, and is first supported upon the drying deck 22, and is worked forwardly over the burning decks 23 and the final unburned residue passes to the grates 29 where the burning is completed. Air passes inwardly 40 through the flues 34 and travels downwardly therein and is preheated and enters the chamber 37. Such preheated air passes through the openings in the vertical grates 24 and travels forwardly between the burning decks and then 45 enters the combustion chamber 13. This air passes rearwardly over and in contact with the refuse upon decks 22 and 23. After the refuse upon the deck 22 becomes sufficiently dried, it is worked forwardly over the burning decks 23 by 50 implements which may be inserted through the stoke openings 44 or 46 or through the opening 46. When passing over the burning decks the dried refuse is subjected to intense heat and is consumed for the greater portion, but the 55 residue passes upon the grate 29, where the combustion is completed, preheated air being supplied beneath this grate through the passage 38 upon the manipulation of the damper 39. During this drying and burning operation of the 60 high water content refuse, combustible gases and vapors are driven off and become mixed with the products of combustion and pass through the down flues 42 and enter the gas combustion chamber 40. When within the chamber 40, these 65 gases ignite producing an intense heat which raises the temperature of the drying deck 22 so that it is efficient in drying the refuse. The chamber 40 has the baffles 43 arranged therein so that the combustible gases are caused to travel 70 in a tortuous path and turbulence of the same is effected, which aids in the complete combustion and deodorization. The combustion of these gases is completed in the chamber 40 as stated, and a proper damper may be installed in the 75

passage 44, to properly regulate the egress of the gases to the stack so that the bridge 22 will have proper heat exchange with the gases. By virtue of the dome-shaped surface 30 of the top of the combustion chamber, the maximum reflection of heat upon the burning and unburned refuse is obtained, which materially aids in the proper combustion of the material.

It is to be understood the form of my invention herewith shown and described is to be taken as a preferred example of the same and that various changes in the shape, size and arrangement of parts may be resorted to, without departing from the spirit of my invention or the scope of the subjoined claims.

Having thus described my invention, I claim:

1. In an incinerator, a casing having a main combustion chamber, a bottom for the combustion chamber including a main drying deck and burning decks arranged in stepped relation, the burning decks having openings arranged between them for the passage of air, the combustion chamber having a top provided with a generally spherically curved inner surface for transmitting heat over all of the decks, and also having a charging opening for feeding the material upon the drying deck, means for providing an air-receiving chamber beneath the burning decks and having communication with the openings between the burning decks, said casing having down flues for preheating air and supplying the same into the air-receiving chamber, means for providing a gas combustion chamber beneath the drying deck, said casing having ducts which lead from the main combustion chamber above the drying deck and into the gas combustion chamber beneath the drying deck.

2. In an incinerator, a casing having a main combustion chamber, a bottom for the combustion chamber including a drying deck and burning decks arranged in stepped relation, means for providing openings between the burning decks, the combustion chamber including a top having an inner curved heat transmitting surface, means providing an ash pit within the casing in advance of the lowermost burning deck and openings leading into the ash pit, a grate covering the ash pit, means providing an air-receiving chamber beneath the burning decks and having communication with all of said openings, said casing having air preheating flues leading into the air-receiving chamber, means for providing a gas combustion chamber beneath the drying deck, means for effecting the turbulence of gases within the gas combustion chamber, means of communication between the main combustion chamber and the gas combustion chamber, and material inlet means leading into the combustion chamber above the drying deck.

3. In an incinerator, a casing having a main combustion chamber, a bottom for the combustion chamber including a drying deck, burning decks and a grate disposed in stepped relation, means for providing an air-receiving chamber beneath the burning decks and openings between the burning decks and an opening extending beneath the grate with all of the openings in communication with the air-receiving chamber, a top for the main combustion chamber having an inner generally spherically curved surface extending over all of the decks and the grate, said top having a charging opening so that material may be fed upon the drying deck, burners arranged within the combustion chamber and disposed near the burning decks, preheating flues

for introducing preheated air into the air-receiving chamber and extending across the sides of the main combustion chamber, means for providing a gas combustion chamber beneath the drying deck, baffles disposed within the gas combustion chamber to effect the turbulence of the gases, and a duct communicating with the main combustion chamber and with the gas combustion chamber.

4. In an incinerator, a casing having a main combustion chamber and provided near one end with a stoke opening and near the opposite end with a stoke opening, doors for covering the openings, a bottom for the combustion chamber including a drying deck, burning decks and a grate disposed in stepped relation between said openings, means for providing an ash pit beneath the grate, means for providing an air-receiving chamber beneath the burning decks and openings between the burning decks and an opening leading into the ash pit with all of the openings in communication with the air-receiving chamber, a damper for controlling the passage of air through the opening leading into the ash pit, means for supplying preheated air into the air-receiving chamber, a top for the main combustion chamber having an inner surface which is generally spherically curved and extends over the drying and burning decks and grate, said top having an opening above the drying deck for the passage of material thereon, burners arranged within the main combustion chamber near the burning decks, and means for providing a gas combustion chamber beneath the drying deck and having communication with the combustion chamber.

5. In an incinerator, an elongated casing having a main combustion chamber provided at one end with an elevated stoke opening, a door to cover the opening, a bottom for the main combustion chamber comprising a drying deck arranged adjacent to the stoke opening and burning decks and a grate which are arranged in stepped relation with each other and with the drying deck and leading downwardly from the drying deck, means for supplying air between the burning decks and through the grate, such air travelling upwardly over the burning decks and drying deck, a top for the combustion chamber having a generally spherically curved inner surface for transmitting heat over the drying deck, burning decks and grate, said top having an opening for feeding material upon the drying deck, burners arranged within the combustion chamber near the burning decks and means for providing a gas combustion chamber beneath the drying deck, said gas combustion chamber having a flue which leads from the main combustion chamber near and above the drying deck.

6. In an incinerator, a casing having a main combustion chamber provided near one end with an elevated stoke opening, a door to cover the opening, a bottom for the main combustion chamber comprising a drying deck disposed adjacent to the stoke opening and burning decks and a grate which are arranged in stepped relation with each other and with the drying deck and leading downwardly from the drying deck, means for passing air at different elevations between the burning decks and through the grate, such air travelling upwardly over the burning deck and drying deck, a top for the combustion chamber having an opening for discharging material upon the drying deck, burners arranged within the combustion chamber near the burning

decks, and means forming a gas combustion chamber beneath the drying deck and having communication with the main combustion chamber near and above the drying deck.

- 5 7. In an incinerator, a casing having a main combustion chamber provided near one end with an elevated stoke opening, a door to cover the opening, a bottom for the main combustion chamber comprising a substantially imperforate 10 drying deck disposed adjacent to the stoke opening and substantially imperforate burning decks and a grate which are arranged in stepped relation with each other and with the drying deck and leading downwardly from the drying deck, 15 means for passing air at different elevations between the burning decks and through the grate, a top for the combustion chamber having an opening for charging material upon the drying deck, burners arranged within the combustion 20 chamber near the burning decks, and means for exhausting gases from the combustion chamber at a point near and above the drying deck.
8. In an incinerator, a casing having a main combustion chamber, a bottom for the combustion chamber including a substantially imperforate 25 drying deck and substantially imperforate burning decks arranged in stepped relation, and having means disposed between them at different elevations for the passage of air, and a top for the combustion chamber having an inner generally spherically curved surface.

9. In an incinerator, a casing having a main combustion chamber, a bottom for the combustion chamber including a drying deck and burning decks arranged in stepped relation, said casing having means by which material may be fed upon the drying deck and worked therefrom over the burning decks, means for passing air at different elevations between the burning decks, 30 burners arranged within the combustion chamber near the burning decks, a top for the combustion chamber having an inner generally spherically curved surface, and means for exhausting gases from the combustion chamber at a point 35 near and above the drying deck.

10. In an incinerator, a casing having a main combustion chamber including a wall toward which the heated gases travel, a bottom for the main combustion chamber comprising an imperforate 40 drying deck extending to the wall in the direction of travel of the heated gases, substantially imperforate burning decks and a grate arranged in stepped relation with each other and the drying deck and extending downwardly from the drying deck, means for introducing air into 45 the main combustion chamber to support combustion, a top for the combustion chamber having an opening for feeding material to be burned upon the drying deck, means providing a gas combustion chamber beneath the drying deck, and a duct leading from the gas combustion chamber into the main combustion chamber at a point above the drying deck.

11. In an incinerator, a casing having a combustion chamber including a wall toward which the heated gases travel, an imperforate drying deck extending to the wall in the direction of travel of the heated gases and having associated therewith means to permit of the deposit of material thereon to be burned, the opposite end of the drying deck being spaced from the wall of the casing remote from the first named wall, a substantially imperforate burning deck and a grate arranged in stepped relation with respect to the 60 burning deck and disposed between the free end 65

of the drying deck and the last named wall, means for supplying air into the combustion chamber to support combustion therein, means for providing a gas combustion chamber beneath the drying deck, and a duct leading from the gas combustion chamber into the main combustion chamber. 5

12. In an incinerator, a casing having a combustion chamber including a wall toward which the heated gases travel, an upstanding wall arranged within the casing and spaced from the top of the casing and the first named wall and the wall of the casing disposed opposite and remote from the first named wall, a drying deck extending from the upstanding wall to the first 15 named wall in the direction of travel of the heated gases, means including the drying deck and upstanding wall for providing a gas combustion chamber beneath the drying deck, said drying deck having means associated therewith to 20 permit of the feeding of material to be burned upon the drying deck, a burning deck and a grate arranged in stepped relation to each other and disposed between the upstanding wall and the remote opposite wall, means for supplying air 25 into the combustion chamber to support combustion therein, and a duct leading from the gas combustion chamber into the main combustion chamber. 30

13. In an incinerator, a casing having a combustion chamber including a wall toward which the gases travel, an upstanding wall arranged within the casing and spaced from the first named wall and the wall of the casing disposed opposite to and remote from the first named wall, a drying 35 deck extending from the upstanding wall to the first named wall in the direction of travel of the heated gases, means including the drying deck and upstanding wall for providing a gas combustion chamber beneath the drying deck, said 40 drying deck having means associated therewith to permit of the feeding of material to be burned upon the drying deck, a burning deck and a grate arranged in stepped relation to each other and disposed between the upstanding wall and the 45 remote opposite wall, the burning deck having an air passage therebeneath which leads into the combustion chamber and means providing an air passage which discharges beneath the grate, means for supplying air to said air passages, and 50 a duct leading from the gas combustion chamber to the main combustion chamber.

14. In an incinerator, a casing having a combustion chamber, a drying deck arranged therein and having means associated therewith to permit of the deposit upon the drying deck of material to be burned, a plurality of burning decks and a grate arranged in stepped relation to each other and to the drying deck and extending downwardly from the drying deck, the burning decks 60 having air passages beneath the same which lead into the combustion chamber at different elevations and means providing an air passage discharging beneath the grate, means for supplying air to all of the passages, means for providing a 65 gas combustion chamber beneath the drying deck, and means of communication between the gas combustion chamber and the first named combustion chamber. 70

15. In an incinerator, a casing having a combustion chamber including a wall toward which the heated gases travel, an imperforate drying deck extending to said wall and having associated therewith means to permit of the deposit of material thereon to be burned, the opposite 75

end of the drying deck being spaced from the wall of the casing remote from the first named wall, a substantially imperforate burning deck and a grate arranged between the free end of the drying deck and the last named wall with the burning deck disposed next to the drying deck, the burning deck and grate being disposed at an elevation beneath the upper surface of the drying deck, means for supplying air into the combustion chamber at a point adjacent to the burning deck and next to the drying deck so that the air passes over the burning deck upon entering the combustion chamber, means for providing a gas combustion chamber beneath the drying deck, and means of communication between the gas combustion chamber and the main combustion chamber.

16. In an incinerator, a casing having a combustion chamber including a wall toward which the heated gases travel and a second wall remote from the first named wall, an imperforate drying deck extending to the first named wall and having associated therewith means to permit of the deposit of material upon the drying deck, the opposite end of the drying deck being spaced from the second wall, a substantially imperforate burning deck and a grate arranged between the free end of the drying deck and the second named wall with the burning deck next to the drying deck, the burning deck and grate being disposed at an elevation beneath the upper surface of the drying deck, means providing an air receiving chamber disposed adjacent to the drying deck and having communication with the combustion chamber at a point near the upper surface of the burning deck, means for supplying air into the air receiving chamber, and outlet means for the combustion chamber.

17. In an incinerator, a casing having a combustion chamber, an imperforate drying deck ar-

ranged within the combustion chamber and having means associated therewith to permit of the deposit of material thereon, a substantially imperforate burning deck and a grate arranged to receive material passing from the discharge end of the drying deck and disposed at an elevation below the upper surface of the drying deck, the burning deck being arranged next to the drying deck, means providing an air receiving chamber arranged near the drying deck, a vertical grate disposed adjacent to the burning deck and extending across a portion of the air receiving chamber, means for preheating air and supplying the same to the air receiving chamber, and outlet means for the combustion chamber.

18. In an incinerator, a casing having a combustion chamber, an upstanding wall arranged therein, an imperforate drying deck arranged within the combustion chamber and connected with the upstanding wall and having means associated therewith to permit of the deposit of material thereon, a substantially imperforate burning deck and a grate arranged to receive material passing from the discharge end of the drying deck and disposed at an elevation below the upper surface of the drying deck, the burning deck being arranged next to the drying deck, means for providing a gas combustion chamber beneath the drying deck and upon one side of the upstanding wall and an air receiving chamber upon the opposite side of the upstanding wall, the air receiving chamber being disposed next to the burning deck and projecting above the same for communication with the combustion chamber, means for supplying air into the air receiving chamber, and means of communication between the gas combustion chamber and the main combustion chamber.

MARK H. ALLEN. 40
